FIG. 1 is a top plan view of a tackless carpet stripping showing our new design shown broken away to indicate indeterminate length with the pattern repeating regularly throughout its length;

FIG. 2 is a bottom plan view of FIG. 1;

FIG. 3 is an elevational view taken from the bottom of FIG. 1;

FIG. 4 is an elevational view taken from the bottom of FIG. 2;

FIG. 5 is an end elevational view taken from the left of FIG. 3;

FIG. 6 is an end elevational view taken from the right of FIG. 3; and

FIG. 7 is a fragmentary perspective view thereof.
